UNITED STATES PATENT OFFICE.

CHARLES H. CASPAR, OF PHILADELPHIA, PENNSYLVANIA.

AEROPLANE.

1,360,621.

Specification of Letters Patent. Patented Nov. 30, 1920.

Application filed October 15, 1918. Serial No. 258,282.

To all whom it may concern:

Be it known that I, CHARLES H. CASPAR, a citizen of the United States, residing in Philadelphia, Pennsylvania, have invented 5 certain Improvements in Aeroplanes, of which the following is a specification.

My invention relates to aeroplanes; and one object of my invention is to provide a structure of greater size, greater lifting 10 power, and greater carrying capacity than other structures having a similar object in view, or designed for a similar purpose.

A further object of my invention is to provide a structure particularly available for 15 military purposes and capable of sustaining in flight a relatively large crew beside an operator (or operators) and, in addition, a structure that may be equipped with a main battery of guns having a relatively larger 20 caliber and more effective range than those employed with aeroplanes heretofore constructed or developed.

A further object of my invention is to provide novel means for applying power to 25 drive aeroplane structures; the same being particularly adapted for a structure of the type forming the subject of my invention.

A further object of my invention is to provide a structure having hollow wing vanes with flexible tips; the chambers of 30 such vanes communicating with a power duct (or ducts) through which a stream (or streams) of air will be forced by the propelling means employed.

And a further object of my invention is to provide a boat-like structure, which while 35 it may carry suitable wheel supports or other means whereby it may run upon the ground preliminary to or after flight, may have a suitable floating body in lieu of such wheel supports, as may be desired; my improved 40 structure being designed to rise from the water as well as from the ground.

These and other features of my invention 45 are more fully described hereinafter, reference being had to the accompanying drawings, in which:

Figure 1, is a plan view of an aeroplane structure within the scope of my invention.

50 Fig. 2, is a front elevation of the same.

Fig. 3, is a side elevation.

Fig. 4, is a longitudinal section on the line 55 IV—IV, Fig. 5.

Fig. 5, is a sectional plan view on the line

55 V—V, Fig. 4.

Figs. 6, 7 and 8, are cross sectional views on the lines VI—VI, VII—VII, and VIII—VIII, Fig. 4.

Fig. 9, is an enlarged plan view of one of the wings.

Fig. 10, is a sectional view of the wing, on the line X—X, Fig. 9, and

Fig. 11, is a cross sectional view of a wing, on the line XI—XI, Fig. 9, at its point of attachment with the body.

The body of my improved aeroplane structure, illustrated at 1 in the several views, may be substantially cylindrical and may taper toward the rear, or have any suitable form or shape. This body may be 70 double-walled, of any suitable construction, with suitable braces 2 and ribs 3 constituting the framework of such body, and within the structure and longitudinally of the same a hollow space 4 may be provided, which I 75 term a power duct. If more than one propeller is employed, there may be a power duct for each propeller. Connected to the body 1, externally of the same at several points throughout its length are a series of 80 hollow wings 5, having pivotally mounted tips 6, the present structure showing four pairs of such wings connected to the sides of the body at substantially the horizontal axis of the same, while two other pairs may 85 be secured to the sides of the body at points intermediate the three forward pairs of wings and near the upper portion of such body. It will be understood that I may employ a greater or less number of such wings, 90 depending upon the size of the structure, and that their position with respect to the body is not arbitrary. The body may be provided with port holes or windows 7, closed by the usual form of dead lights common to ship construction.

Within the lower portion of the hollow body below the floor 8 of the power duct; which portion may be water-tight so as to be capable of floating in water, I provide 100 a series of compartments 10, 11, 12, 13 and 14, as follows: The navigator's room, indicated at 10, is at the forward part of the structure and may be provided with suitable controlling members 15, having suitable connections 16, whereby the pivoted tips 6 of the wings may be operated as well as the rudder 17. The latter may be carried by a shaft 18 suitably mounted at the tail of the structure. Behind the navigator's room 105 130

is the gun room, indicated at 11, within which a gun (or guns) 19 may be mounted for shooting downwardly or through the bottom of the structure, and aft of the gun room 5 may be located the engine room 12, preferably centrally of the structure. With fuel tanks 20 flanking the same, and suitable oil receptacles 21 disposed below the engine platform 22 and within the shell of 10 the aeroplane structure. Aft of the engine is the compartment 13 constituting the crew's quarters, and aft of the same the compartment 14 provides a mess room. Below the crew's quarters storage space, indicated 15 at 23, may be provided for bombs and other munitions, and in such space a bomb firing pit 24 may be located at any suitable point; here shown as substantially midway the length of the aeroplane structure. It will 20 be understood that any part of the structure may be modified to suit convenience or necessity when the structure is in use.

If designed to rise from and descend to the surface of a body of water, so-called 25 landing gears are not required, but for the purpose of moving the structure over the ground when not in flight, or when commencing flight from the ground and landing, suitable brackets 25, carrying wheels 30 26 may be attached to the body of the structure.

As a military structure, the upper portion of the body may be provided with an armored gun room 30; suitably mounted 35 guns being indicated at 31. An inclosed shaft 33 provides access from the crew's quarters to the armored gun room, and within the said shaft a suitable ladder or staircase 34 may be provided, with a suitable 40 ammunition hoist 35 conveniently arranged or paralleling the ladder.

The wings may be of the peculiar shape and character clearly indicated in Figs. 9, 10 and 11, and they may constitute a hollow 45 frame 5, which may be of the usual stream line contour, and the inner ends of such wing frames may be rigidly attached at 40 to the body 1 of the aeroplane structure; the openings leading to the hollow spaces 50 of the same registering with openings 41 in the wall of the hollow space of the aeroplane structure which I have termed the power duct. The wall of the hollow space in each wing is provided with an opening 42 55 through which air entering such hollow wing may escape, and while this opening may be disposed at any convenient point, I have shown it at the rear of such hollow space and under the wing.

60 Each wing will be preferably provided at its extremity with a movable tip 6, connected to the wing by a hinge joint, the rod 43 of which joint constitutes a shaft; a suitable bearing 44 for its inner end being mounted on the body of the aeroplane, and

this end of the shaft is preferably provided with an operating wheel 45 over which the connecting tiller ropes 16 will pass and thence to the controls of the navigator's room, so that such pivoted tips may be operated as desired. It will be understood that the tips of the oppositely placed wings may be connected to operate together to neutralize the pressure action, and that if desired each wing tip may be independently 75 operated.

A propeller 50, diagrammatically illustrated, may be mounted at the forward end of the power duct, and the same may be provided with any desired number of blades. 80 It will be understood, of course, that more than one propeller may be employed, and that the disposal of the propelling means is not arbitrary. The propeller (or propellers) may be operatively connected with 85 the motive means employed by any suitable or approved mechanism common to structures of the same general type.

The body of the car may be substantially circular in cross section, tapering to a size 90 materially smaller than the main portion of the same, and pivotally connected to the end is the rudder 17, of suitable construction, mounted on the shaft 18, journaled in suitable bearings 51 carried by the tail of the 95 frame; said shaft having a wheel 52 with a tiller rope 16^a passing to one of the controls in the navigator's room, whereby such rudder may be shifted laterally in either direction as may be necessary or desirable in 100 the operation of the structure.

The operation of my improved structure is substantially as follows:

The propelling means being in action, the motion will create what is commonly known 105 as thrust, which will tend to pull the structure forward and at the same time force the air rearwardly throughout the power duct (or ducts) at a velocity which may be as great as 200 miles per hour. Under such 110 conditions the structure would, as in the case of an ordinary aeroplane, start to move forward by means of the thrust of the propelling means, and the air passing through the slots in the hollow wings would create 115 an upward thrust on the wings. If the hinged ends of wings were turned down so that this rearwardly discharging air impinges on the same, the tendency of the pressure is to neutralize the forward thrust 120 and force the structure rearward. At a sufficient velocity the pressure under the wings will raise the structure which, after it has attained a certain height, if the movement of the propelling means or the velocity of the air passing through the power duct is lowered, the machine will descend. While the structure is in vertical flight, the sustaining power and the thrust power are 125 neutralized by turning down the movable 130

wing tips which, if still further lowered, will overcome the neutral point of drift and tend to force the machine rearwardly.

The reverse of this action, or the raising 5 of the movable wing tips, will overcome the neutral point of drift in an opposite manner and permit the structure to go forward. By proper adjustment of the movable wing tips and rudder while in a sustained position, the structure may turn on its own 10 axis, or nearly so. Preferably two or more of the rear wing tips are connected to a separate control and may be used to control or balance the structure, or for flight up or 15 down, at an angle.

It follows that, without departing from the spirit of my invention, any source of power may be used to accomplish the purpose; for instance, steam pressure may be 20 used to create the desired blast of air in the power duct, or compressed air may be used. Further, the propelling means may be placed at any desired position in the structure, as it is not necessary to place it at the 25 forward end. Any desired number of propellers may be employed as may be necessary for the size of the structure.

I claim:

1. An aeroplane structure comprising a hollow body having a power duct in the 30 upper portion of the same, hollow wings communicating with said power duct, propelling means mounted in the power duct, and chambers constituting crews' quarters, fuel and munition spaces below said power 35 duct.

2. An aeroplane structure comprising a hollow body having a power duct in the upper portion of the same, hollow wings with outlets communicating with said power 40 duct, a propeller within said power duct, and chambers constituting crews' quarters, fuel and munition spaces below said power duct.

3. In an aeroplane structure, a hollow 45 body, a power duct in said body, hollow wings communicating with said power duct, a space for engine, fuel, munitions and crews' quarters below said power duct, a gun chamber at the upper portion of the 50 structure, and a shaft between the crews' quarters and said gun chamber passing through the power duct.

CHARLES H. CASPAR.
